GARAGE DOOR CONSTRUCTION

William D. Ferris, Sterling, Ill., assignor to Frantz Manufacturing Co., Sterling, Ill., a corporation of Illinois

Application March 25, 1937, Serial No. 132,913

8 Claims. (Cl. 20—16)

This invention relates to garage doors, or similar doors, and particularly to those that are adapted to open upwardly into an overhead open position.

Generally stated, the object of the invention is to provide a novel and improved construction and arrangement whereby a garage door of this general character is constructed and mounted in a way that will more satisfactorily enable it to accommodate itself to varying conditions of doorway and building construction.

A special object is to provide a novel construction and arrangement whereby garage doors of this kind may be used in pairs, say, for a two-car garage, in a manner that will tend to obviate the necessity of using anything between them, inside of the building, that might be quite liable to injuriously engage the sides of the automobiles.

Another object is to provide a novel construction and arrangement whereby the opening movement, as well as the closing movement, of the door, is retarded at the end of either movement by friction means that can be easily adjusted or regulated to insure the desired retarding effect, in accordance with the size and weight of any particular door.

It is also an object to provide certain details and specific features of construction tending to increase the general efficiency and desirability of a garage door of this particular character.

To the foregoing and other useful ends, the invention consists in matters hereinafter set forth and claimed and shown in the accompanying drawings in which—

Fig. 1 is a vertical section of a garage door embodying the principles of the invention, showing adjacent portions of the building.

Fig. 2 is a fragmentary perspective view of certain portions of the support upon which the door is mounted for opening and closing movement.

Fig. 3 is a perspective of one of the parts shown in Fig. 2 of the drawings.

Fig. 4 is a horizontal section on line 4—4 in Fig. 1 of the drawings, on a smaller scale.

Fig. 5 is an enlarged vertical detail section on line 5—5 in Fig. 1 of the drawings.

Fig. 6 is a side elevation of the parts shown in Fig. 5 of the drawings.

Fig. 7 is a diagrammatic view showing certain of the elements of Figs. 5 and 6 in separated condition and in perspective.

As thus illustrated, the invention comprises a pair of upright rectangular garage doors 1 and 1, mounted in the two doorways in the front of

the garage building 2, as shown in Figs. 1 and 2 of the drawings. It will be seen that each door is of a width to swing through its doorway, but is preferably of a height to normally engage the top portion 3 of each doorway immediately inside thereof, as shown in Fig. 1 of the drawings, while in this closed position, each door has its lower edge resting upon the floor of the garage.

Each door has a pair of upright angle irons 4 secured to the back or inside thereof, and each angle iron has its rearwardly extending flange formed with a gap at 5, and the horizontal channel irons 6 are mounted in these gaps or notches, as shown more clearly in Fig. 2 of the drawings. To hold the channel irons 6 for endwise adjustment in these gaps or notches, guide plates 7 are bolted to the rearwardly extending flanges of the angle irons 4. For each door, there is a horizontal channel iron 8 bolted to the back or inside of the door, with the adjacent end portions of the channel irons 6 clamped therein by bolts 9 that extend through the doors. The channel irons 8 may have holes or slots for said bolts, and the channel irons 6 may also have bolt holes of this character, whereby the channel irons 6 are adjustable endwise in the channel irons 8, for doors of different widths, or for different distances between the sides of the building. The outer end of each channel iron 6 has a right angle channel arm section 10 secured thereto by rivets and plates 11, as shown more clearly in Fig. 2 of the drawings, so that these horizontal and parallel arms 10 are rigid with the channel irons 6, and are thereby susceptible of adjustment toward and away from each other, by means of the bolts 9 previously described. Each arm 10 has a brace 111 extending upwardly from a swivel eye 12 on the arm to an eye 13 on a bracket plate 14 secured to the back or inner side of the door. Thus, these braces 111 can assume different positions, according to the distance between the arms 10, for garage buildings having varying or different structural conditions. Each arm is pivoted on the building at 15, and each arm is preferably provided with a series of holes 16 for adjustably connecting the lower end of a spring 17 thereto, the upper end of each spring being preferably fastened to the building at 18, by any suitable or desired means.

Thus, each door normally occupies its closed position, as shown in Figs. 1 and 4 of the drawings, but, with the assistance of the springs, may be raised into the position shown in dotted lines in Fig. 1 of the drawings, in which position the

lower end portion of each door rests against the under side of the top portion 3 of its allotted doorway. The springs help to raise the doors into open position, and then cushion the downward movement of the doors into closed position.

When two doors are arranged this way, as close together as possible, something must be provided, in an upright position, between the adjacent arms 10, to support the pivots 15 of these arms. If a support of that kind should be vertical, it would then be far enough within the building to endanger the sides of the automobiles. Therefore, to avoid such danger, an inclined fixed support 19 is provided, which extends upwardly from a point 15 between the adjacent lower corners of the two doors, to a point above on the building some distance back from the front of the building, so that the upper and lower ends of this inclined support are held in fixed position. This inclined support 20 19 is of advantage, it will be seen, for the reason that it provides clearance below it, at its lower portion, for the wheels and foot-board and mud-guards of the vehicles, which are the things on the automobiles that are most likely to be injured 25 by a side swerve in driving the vehicles into and out of the building.

Preferably, each pivot 15 is constructed as shown in Figs. 5, 6 and 7 of the drawings, in order to provide a retarding friction at the end 30 of the upward movement of the door into open position, and also at the end of the downward movement of the door into closed position. For that purpose, each arm 10 has a bracket plate 20 secured thereto, as by means of bolts inserted 35 through holes 21 in said plate, and through the arms. Each plate 20 has a squared hub portion 22, and a metal disk 23, with a substantially rectangular opening 24, is mounted on said squared portion of the plate, the squared portion extending 40 through and substantially fitting this opening. This disk 23 is also provided with diametrically opposite curved slots 25. A disk 26 of asbestos, or other suitable fibrous material, engages the face of the disk 23, and a cup-shaped 45 or flanged disk 27 has its inner flat surface arranged to engage the other side of the disk 26, as shown in Fig. 5 of the drawings. Bolts 28 are inserted through all three disks, and through the slots 25, to clamp the three disks together, and 50 by means of these bolts the friction between the disks can be adjusted or regulated to suit the conditions, and in accordance with the weight of the door and the tension of the said springs. The disks 26 and 27 are provided, respectively, 55 with round openings 29 and 30 to receive the hub portion 22, so that these disks 26 and 27 will have rotary movement on said hub, while the disk 23 is held against rotation on said hub and will move in unison with the swinging movement of 60 the arm 10, when the doors are opened and closed. A bracket plate 31 is secured to the building, in rigid and stationary position, for each pivot 15; and for each pivot, there is a stud 32 extending through the bore or opening 33 of the plate 20, 65 formed at its outer end with a head 34, and at its inner end with a reduced portion 35 which extends through the opening 36 in said bracket plate, this reduced portion 35 being riveted over to make the stud 32 rigid with said bracket plate. 70 The latter is also provided with outwardly bent lugs 37 and 38, arranged substantially ninety degrees apart, as shown. With this arrangement, when a door is raised into open position, the disk 23 of each pivot turns on the axis of the latter 75 and, by frictional contact, rotates the disk 26

and the disk 27 in unison, so that no friction is exerted during the main portion of the opening movement of the door. However, when the lug 39 on the disk 27 strikes the lug 38 previously mentioned, the rotation of the disks 26 and 27 is stopped, and the disk 23 then rotates alone until the ends of the slots 25 engage the bolts 28 previously mentioned, and it is during such final rotation of the disk 23 that sufficient friction is developed between this disk and the disk 27 to retard the end portion of the opening movement of the door. Thereafter, when it is desired to close the door, all three disks rotate with a swinging motion of the arm 10 until the lug 39 strikes the lug 37 previously mentioned, and then again the disk 23 rotates alone in frictional contact with the disk 26, thereby frictionally retarding the end portion of the closing movement of the door. Preferably, each disk 27 is provided with another lug 40, diametrically opposite the lug 39, so that the same disks can be used either at the right or the left. In this way, the plates 31 can all be alike, but those at one side will have their lugs 37 and 38 in position to cooperate with the lug 39, while those at the other side of the door will be turned around to have their lugs 37 and 38 in position to cooperate with the lug 40 instead.

Thus, the pivot of each arm 10 has a friction device therein, that develops friction at the end 30 of the opening movement of the door, and at the end of the downward or closing movement of the door, sufficiently to bring the door softly and easily into open position, and softly into closed position, when the friction devices are properly 35 adjusted or regulated to insure the desired or requisite degree of friction necessary for that purpose.

This application discloses matter common to that disclosed in copending application to same 40 inventor, Serial #97,876, filed Aug. 26, 1936.

What I claim as my invention is:

1. In a garage door, a single rigid door section normally in vertically disposed position in the doorway of the building, a horizontal arm rigid 45 with and extending at right angles to the back or inside surface of the door, an inclined fixed support extending upwardly and inwardly of the doorway, from a point adjacent the lower corner of the door, at the front of the building, to a point above and in rear of its lower end, and a pivot for said arm, on said inclined support, the latter providing clearance below its lower portion for the mud-guards and foot-board of an automobile, the door thus constructed having a horizontally disposed overhead open position, when moved upwardly about the axis of said pivot. 50

2. A structure as specified in claim 1, comprising another similar door, with a similar rigid arm, the two doors being side by side in the same vertical plane, and a pivot for the latter on said inclined support, so that the latter is between the two arms, whereby the clearance below said inclined support is effective for an automobile at either side thereof. 55

3. In a garage door, a single rigid door section normally occupying a vertically disposed position in the doorway of the building, a horizontal channel iron on the back or inside surface of the door, the length of said channel iron being 60 less than the width of the door, horizontal parallel arms joined to sections of channel iron that are slidable endwise in the channel of said first-mentioned channel iron, so that the distance between said arms may be changed, vertically 70

disposed angle irons on the back of the door, provided with guiding means for said adjustable sections of channel iron, and pivots for said arms on the structure of the building, whereby the said door has a horizontally disposed over-head open position.

4. A structure as specified in claim 3, comprising inclined braces extending inwardly and downwardly from the back of the door to said arms, and means whereby the upper and lower ends of said braces are adjustably and movably engaged with the back of the door and said arms, to accommodate the adjustment of the latter toward and away from each other.

5. In a garage door, a single rigid door section normally disposed in substantially vertical position in the doorway of the building, an arm rigid with the inside surface or back of the door, and a pivot for said arm on the structure of the building, said pivot comprising a polygonal hub on said arm, a metal disk provided with a central opening formed to receive said hub, and with curved diametrically opposite slots, a disk of friction material engaging said first-mentioned disk, a third disk having bolts extending through the friction disk and the slots of the first disk, a stationary bracket plate secured to the building structure and provided with outwardly project-

ing lugs, with a projection on the periphery of said third disk operating between the lugs on said bracket plate, and a stud inserted through the arm and hub and fastened to said bracket plate, so that said arm and hub and first-mentioned disk oscillate in unison about the axis of said stud, and said curved slots permitting slippage between disks, thereby providing lost motion retarding friction for the end portion of both the opening or closing motion of the door.

6. A structure as specified in claim 5, the lugs on said bracket plate being spaced substantially ninety degrees apart, on the line of a circle struck from said axis.

7. A structure as specified in claim 5, said third disk having another projection diametrically opposite its first-mentioned projection, so that this disk can be used as either a right or a left, with bracket plates which are exactly the same in form, but differently positioned on the building structure.

8. A structure as specified in claim 5, said first-mentioned disk being held against rotation relatively to the arm, by the engagement of the disk with said hub, but the other two disks having oscillatory motion upon and relative to said hub, and thereby relative to said arm.

WILLIAM D. FERRIS.
